V. BABCOCK.

Gate.

No. 56,693.

Patented July 31, 1866.

UNITED STATES PATENT OFFICE.

VANTUYL BABCOCK, OF MARSHALL, MICHIGAN.

IMPROVEMENT IN GATES.

Specification forming part of Letters Patent No. **56,693**, dated July 31, 1866.

To all whom it may concern:

Be it known that I, VANTUYL BABCOCK, of the city of Marshall, in the county of Calhoun and State of Michigan, have invented a new and useful Improvement in Gates; and I do hereby declare that the following is a full, clear, and exact description of the construction and operation of the same, reference being had to the annexed drawings, making a part of this specification, in which—

Figure 1 is an isometric perspective view of fence-sections and gate. Fig. 2 is a vertical lateral section in the line x.

Similar letters of reference indicate like parts in both figures.

This invention relates to an arrangement of parts by the use of which a recess may be readily constructed to receive a gate moved therein horizontally on rollers set between permanent guide-rails; and, the better to enable others skilled in the art to construct my invention, I will now proceed more particularly to describe the same.

My arrangement does not require any special mode of constructing the fence-sections to which the gate is applied, with the exception of setting two of the posts somewhat higher than the rest, as seen in Fig. 1, where A A represent the two high, and B B the ordinary, posts of the fence.

C indicates the fence rails or boards, which may be framed into the posts or nailed on in the common way, a facing-strip, D, being attached, as usual with this kind of fence.

A supplementary post, E, is set opposite to and outside of the posts A at a distance from it equal to the full thickness of the center portion of the gate, and a guide-rail, F, is firmly secured at the upper end between the main and supplemental posts.

I provide the gate with an upper rail, G, sufficiently deep to prevent sagging, which rail projects a short distance beyond the inner stile or cleat facings, H, and attach to each side of this projecting end a piece of plank, (indicated at I,) which extend upward sufficiently to receive two rollers, R' and R'', between, in such manner as to embrace the sides and edges of the guide-rail F aforesaid, but with sufficient looseness to permit a free sliding movement. I usually round the upper ends of the saddle-planks I close to the upper roller and cap them with sheet-iron.

The gate is mainly supported by its upper rail, G, resting and sliding upon the upper

side of another roller, R³, hung between the two long outer posts.

J represents a short supplemental post, which is set in the ground opposite the fence-post B, so as to form a recess to receive the end of the gate when shut. The upper ends of these two posts are usually covered by a cap, as indicated by the dotted lines.

My usual mode of securing the gate when shut is by means of a fixed latch-piece, L, which is notched so as to catch in the lower cross-bar, b.

To open and shut the gate, it is merely pushed by hand back and forth upon the rollers, being guided at one end by the roller-saddle and at the other by the two posts, and it will be readily seen that, as the gate must have some lap, or, in other words, that, as the gate must be wider than the opening it is intended to close, the overhang, when it is nearly closed, will not produce sagging, as the roller R² bears against the under edge of the guide-rail F, and the distance from such bearing to the fulcrum or point where the gate is supported by its upper rail on the roller R³ is sufficiently long to prevent any injurious strain by the overhanging weight.

My mode, as described herein, of hanging a gate requires no special construction in the gate itself, excepting as it relates to the upper rail, as heretofore described, and is peculiarly applicable for use on farms, where large gates are so frequently required in new positions, being as readily applied to an old inclosure as to an entirely new construction.

To attach it to a fence already erected it is only necessary to remove one panel, set the supplemental posts, and lengthen out the two fence-posts of the adjacent panel, so as to get a firm attachment of the guide-rail F.

I do not claim, broadly, sliding a gate parallel with the fence on rollers, for this is old; but,

Having described my invention, what I claim as new, and desire to secure by Letters Patent, is—

The arrangement and combination of the rail G, saddle-pieces I, rollers R' R'' R³, and supplemental posts E and J with an ordinary gate and fence, substantially in the manner and for the use herein specified.

VANTUYL BABCOCK.
